(57) **CLAIM**

The ornamental design for a housing for an electronic device, as shown and described.

DESCRIPTION

FIG. 1 is a perspective view of a housing for a electronic device showing our new design;

FIG. 2 is a front elevation view of the housing for an electronic device of FIG. 1;

FIG. 3 is a rear elevation view of the housing for an electronic device of FIG. 1;

FIG. 4 is a top plan view of the housing for an electronic device of FIG. 1; and,

FIG. 5 is a left side elevation view of the housing for an electronic device of FIG. 1, the right side elevation view of the housing for an electronic device being a mirror image of the left side elevation view.

A view of the bottom has been omitted since the bottom is devoid of surface ornamentation and forms no part of the claimed design.

The broken lines shown in the views are included for the purpose of illustrating portions of the housing for an electronic device that form no part of the claimed design.
